INTERNAL COMBUSTION ENGINE

Filed Dec. 4, 1931

UNITED STATES PATENT OFFICE

1,924,847

INTERNAL COMBUSTION ENGINE

Herbert C. Edwards, Detroit, Mich., assignor to
 Packard Motor Car Company, Detroit, Mich.,
 a corporation of Michigan

Application December 4, 1931. Serial No. 579,002

11 Claims. (Cl. 251—144)

This invention relates to internal combustion engines and more particularly to the valve mechanism thereof.

An object of the invention is to provide a new and novel manner of interconnecting engine valve stems with their spring collars.

Another object of the invention is to provide means for interconnecting the valve stems of internal combustion engines with the valve closing means thereof in a manner obviating wear and consequent loosening of the associated parts.

A further object of the invention is to provide a valve stem of an internal combustion engine with a key member for securing a valve spring retaining and supporting collar thereto, the key member and the stem being so constructed and related as to provide a relatively large area of surface contact therebetween.

Still another object of the invention is the provision of a split tapered key member, for securing a valve stem of an internal combustion engine to the valve spring retaining and supporting collar thereof, which is threaded on the valve stem and is provided with means coacting with means formed on the valve stem to lock the key against rotation relative to the valve stem.

Another object of the invention resides in the provision of a structure of the character specified which is economical to manufacture, light in weight, simple in design and easy to assemble.

Other objects and advantages of the invention will appear from the following description taken in connection with the accompanying single sheet of drawing which forms a part of this specification and in which:

Fig. 1 is a vertical sectional view through a portion of an internal combustion engine showing a poppet valve thereof in elevation and the application of the present invention thereto.

Fig. 2 is a view taken substantially on the line 2—2 of Fig. 1 and looking in the direction indicated.

Fig. 3 is an elevational view showing one section of the split key member forming a part of this invention.

Fig. 4 is an enlarged sectional view showing the formation and relation of the threads of the key member and the valve stem.

Fig. 5 is a fragmentary elevational view of the upper portion of the valve stem.

Referring to the drawing, at 10 is shown a portion of the cylinder block, of a radial type internal combustion engine, having the usual passageway 11 which may be for either the intake or exhaust. The passageway is controlled by a

poppet valve 12 in the usual manner and as shown, the valve and valve gear are housed in a compartment 13 which forms a part of a cylinder head 14 and may be provided with a removable cover 15 permitting access to the compartment. 60 The poppet valve is provided with a stem 16, preferably integral therewith, which is slidably mounted in a bearing sleeve 17 mounted in the cylinder head. A flanged collar 18 is associated with upper end of the valve stem 16 and extending between this collar and a partition 19 of the cylinder head is a compression spring 21, mounted in the well known manner to exert a force upon the valve stem 16 urging the valve head against its seat 9. The valve is opened and 70 closed by suitable tappet mechanism and actuating mechanism therefor (not shown), in a manner familiar to those skilled in the art to which this invention pertains. It will be readily understood that downward or opening movement of the 75 valve 12 is obtained by the action of the tappet mechanism on the end of the valve stem 16 and that upward or closing movement of the valve is secured by the expansive action of the spring 21.

It has been common practice to turn an annular groove in the valve stem 16 near the end thereof thus forming a small flange portion. A split tapered key member is seated in the annular groove and has a small surface on one end thereof which bears against the flanged portion of the 85 valve stem, and a valve spring retaining and supporting collar having a complementary tapered bore is seated on the split key in wedging relation thereto. In such structures, however, the small flange of the valve stem is forced to carry the entire thrust load of the compression spring 21, with the result that the continued opening and closing of the valve leads to excessive wear on the flange portion and on the key members. Furthermore, in constructions of this character, 90 no means are provided for preventing relative rotation of the keys and the valve stems. The combined result of this construction has been that both the keys and the valve stem would become loose and worn, causing jumping of the 95 valve, noise and many other undesirable features.

It has also been proposed to machine the valve stem to form laterally extending grooves and ribs or corrugations near the end thereof. A tapered, split key member having mating or complementary grooves or corrugations has been secured to the ribbed end of the valve stem by a valve spring retaining and supporting collar having a tapered bore therein. This construction, while being an improvement over the construction previously de- 110

scribed, is deficient because of the difficulty in properly machining the corrugations or ribs. It has been found that it is practically impossible to uniformly machine the corrugations on both the valve stem and the key member, with the result that in most cases the entire thrust load of the compression spring is carried by one or possibly two corrugations. This situation results in the corrugation, which does carry the load, becoming chipped and worn at its edges or sides so that a loose fit results with the consequent disadvantages. In some cases the parts have become so worn due to these conditions that the keys have dropped out into the engine mechanism causing serious damage.

Another conventional method employed in this connection is to form the valve stem with screw threads thereon and to provide a split key member having mating screw threads. The key member is screwed on the valve stem and is also held in place by a spring collar having a tapered bore. Structures of this character have been reasonably satisfactory, but serious difficulty has been experienced in this type of device because the key member tends to "back off" the valve stem or unscrew itself therefrom due to the tendency of the spring collar to rotate. When the key member partially unscrews itself, it will be apparent that the tension of the closing spring is changed, thereby affecting the precision setting which must be maintained for efficient operation of the valve. Keys formed in this manner frequently become unscrewed to a point where they drop off the valve stem and allow the collar and spring to do likewise.

In the present invention the disadvantages, above pointed out, are obviated by a structure in which the key member is secured to the valve stem by screw threads, and the split key member is non-rotatably mounted on the valve stem so that relative movement of these parts is impossible. The invention also provides screw threads formed in a particular manner whereby a relatively large surface contacting area between the parts is secured.

As shown, the upper end of the valve stem is provided with a screw thread 22 which consists of several convolutions having a uniform pitch. The key member as shown comprises two segmental portions, 23 and 24 having screw threads 25 formed therein which mate with the screw threads formed on the valve stem. These mating spiral screw threads on both members, because of their uniform pitch, tend to provide a relatively large surface contacting area between the key member and the valve stem.

To further obtain a greater surface engagement between the sections of the key member and the valve stem, the threads thereof are formed in a manner to secure a maximum surface contact therebetween. As shown, the threads 22 of the valve stem 16 are formed so that the root portions 26 thereof have a radius or curved portion and the crest portions 27 are flat. The complementary threads on the portions 23 and 24 of the key member are formed with a radius or curved portion at their crests 28 and the root portions 29 thereof are substantially curved, as shown, to provide the necessary clearance between the threads.

To further obviate wear of the parts and to prevent the key member from "backing off" the valve stem, it is desirable that these members be locked against relative rotation. To this end, portions of the end of the valve stem 16 on two

sides thereof are removed, forming flat surfaces or faces 31, and each section of the key member is provided, above the threaded portions, with a shoulder 32, and a flat face or shoulder 33 is provided which is adapted to lie against the flat face portions 31 of the valve stem, so that rotation of the key member relative to the valve stem is prevented.

The key member is tapered, as shown, in the usual manner and the spring collar 18 has a complementary tapered bore 34 adapted to encircle the sections of the key member and to secure them on the end of the valve stem with a wedging action. It will be understood that in assembling the device, the spring 21 is first positioned about the valve stem. The collar 18 is then placed in position within the end of the spring and the spring is compressed. The two sections of the key member are then positioned on the end of the valve stem with the threaded portions in mating relation and the flat faces of the key members engaging the flat faces of the valve stem, at which time the collar, under the pressure of the spring, is allowed to slip upwardly over the key members thus securing them tightly in position with a wedging action under spring tension.

In manufacturing the parts of this assembly the valve stem threads may be formed on a screw threading machine in the well known manner and the valve stem may then be machined to form the flat face portions 31 on the upper end thereof. The tapered key member may be formed in one piece and then diametrically slotted to form the shoulder portions 32 and the flat faces or shoulder portions 33. The key member may then be machined with the proper tap to form the threads interiorly thereof after which it may be split or cut in half forming two complementary sections each of which is adapted to mate with the threaded portion of the valve stem and the shoulder portions thereof will lie against the flat portions of the valve stem. The parts may then be hardened in any suitable well known manner.

It will be seen from the above description that a device has been provided which is very simple in construction and economical to manufacture. By the provision of spiral screw threads having rounded roots or bottoms, a uniform bearing surface is obtained between the parts the area of which is relatively large. The screw threads may be easily and quickly formed on the parts by a screw thread machine of conventional design so that a uniform pitch to the threads is assured.

While only one specific embodiment has been shown and described, it will be apparent to those skilled in the art that the invention is susceptible of numerous changes in construction and design without departing from the spirit or scope thereof and it is therefore to be limited only by the appended claims.

Having thus described the invention, what is claimed and desired to be secured by Letters Patent is:

1. In an internal combustion engine, a circular valve stem having a portion thereof formed with a flat face and with a threaded portion, a collar encircling the valve stem and having a tapered axial bore, and a split key between the collar and the valve stem, the outer surface of said key being tapered to wedgingly engage the tapered surface of the collar, and a portion of the inner surface of the key being formed with a

flat face engageable with the flat face formed on the valve stem to prevent relative rotation thereof and a portion of the inner surface of the key being threaded to engage with the threaded portion of the valve stem.

2. In an internal combustion engine, a valve stem having screw threads and flat faces formed thereon, a spring supporting collar encircling the valve stem and having a tapered axial bore, a tapered split key wedgingly engaging the tapered surface of the collar and being formed with screw threads engaging the threads on the valve stem in mating relation, the inner peripheral surface of the key being formed with flat faces engaging the flat faces of the valve stem to relatively fix the valve stem and the key.

3. In an internal combustion engine, a circular valve stem having flat faces formed on the periphery thereof and a threaded portion, tapered key means having flat faces engaging the flat faces on the valve stem and a threaded portion engaging the threaded portion of the valve stem, and a valve spring retaining collar engaging the key means.

4. In an internal combustion engine, a circular valve stem having screw threads and a flat face formed thereon, and key means having mating threads engaging the threads on the valve stem, said key means being formed with a flat face engaging the flat face on the valve stem to prevent relative rotation thereof.

5. In an internal combustion engine, a circular valve stem having screw threads formed thereon and having a flat face formed on the periphery thereof, key means having mating threads engaging the threads on the valve stem and being formed with a flat face engaging the flat face on the valve stem, and a spring retaining collar supported on the key means.

6. In an internal combustion engine, a circular valve stem having screw threads formed thereon and having flat faces formed on the peripheral surface thereof, and key means associated with the valve stem comprising a plurality of tapered segmental sections formed with mating threads engaging the threads on the valve stem, said sections having flat faces formed thereon engaging the flat faces on the valve stem.

7. In an internal combustion engine, a circular valve stem having screw threads formed thereon

and having flat faces formed on the peripheral surface thereof, key means associated with the valve stem comprising a plurality of tapered segmental sections formed with mating threads engaging the threads on the valve stem, said segmental sections having flat faces formed thereon engaging the flat faces on the valve stem, and a valve spring retaining collar engaging the segmental sections, the inner surface of said collar being tapered in a manner to co-act with the segmental sections to secure them in position and to secure the collar thereto.

8. In a valve gear for an internal combustion engine, a valve stem having flat faces formed thereon and a threaded portion, tapered key means having flat faces engaging the flat faces on the valve stem and having a threaded portion engaging the threaded portion of the valve stem, and a valve spring retaining collar supported on the key means.

9. In a valve gear for an internal combustion engine, a valve stem having threads formed thereon and having flat faces formed on the periphery thereof, tapered key means entirely supported by the threads on the valve stem and having flat faces engaging the flat faces on the valve stem, and a valve spring retaining collar supported by the key means.

10. In a valve gear for an internal combustion engine, a valve stem having screw threads formed thereon, said threads having a curved portion at their roots and being formed flat at their crests, key means on the valve stem having screw threads engaging the threads on the valve stem in mating relation, the threads on the key means having a curved portion at their crests and being substantially rounded at their roots, and a valve spring supporting collar on the key.

11. In a valve gear for an internal combustion engine, a valve stem having a screw thread formed thereon, key means on the valve stem formed with a screw thread engaging the thread on the valve stem in mating relation, one of the threads having a curved portion at its root and being formed flat at its crest, and the other of said threads having a curved portion at its crest and being substantially rounded at its root, and a valve spring supporting collar on the key.
